SHAVER AND HAIR REMOVER

Gustav Burgeson, Youngstown, Ohio

Application April 20, 1937, Serial No. 138,036

9 Claims. (Cl. 30—43)

The invention relates to a shaver and hair remover and more especially to a safety razor.

The primary object of the invention is the provision of a razor of this character, wherein interfitted relatively movable cylinders provided with slots when in motion will sever hairs for shaving and hair removing purposes, the cylinders being rotatable reversely to each other in their interfitted relationship and also the innermost cylinder is reciprocatory and in this manner assures the positive shaving and hair removing operation in the use of the razor.

Another object of the invention is the provision of a razor of this character, wherein the same is roller acting so that it can be rolled over the skin for shaving and hair removing purposes and will not cut the skin during the use thereof and thus assuring safety against injury while in use.

A further object of the invention is the provision of a razor of this character, which is simple in its construction, thoroughly reliable and effective in operation, readily and easily handled, positive in the working thereof, absolutely safe from cutting the skin during shaving or the act of removing hair from the human body, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is an end elevation of a razor constructed in accordance with the invention.

Figure 2 is an enlarged plan view partly in section.

Figure 3 is a sectional view taken on the line 3—3 of Figure 2 looking in the direction of the arrows; and

Figure 4 is an end elevation of the innermost cylinder of the razor and removed from the outer cylinder.

Similar reference characters indicate corresponding parts throughout the several views in the drawing.

Referring to the drawing in detail, A designates generally the razor constituting the present invention and comprises outer and inner cylinders 10 and 11, respectively, these being formed with circumferentially arranged elongated slots 12 adapted to register with each other and such slots in each cylinder are disposed close to each

other so that when the said cylinders are rotated in opposite directions in their interfitted relation to each other a shearing or cutting action will be set up for shaving and hair removing purposes.

The outer cylinder 10, which functions as a roller in the use of the razor, is of greater length than the inner cylinder 11 and has fitted in any suitable manner in opposite ends thereof, internal gears 13, while the opposite ends of the inner cylinder 11 are formed with spokes 14 extending radially from end hubs 15, these being provided with pinions 16. Interposed between the gears 13 and the pinions 16 are idling gears 17, these being enmeshed with the gears 13 and pinions 16, respectively, so that the outer cylinder 10 under rolling contact with a surface will drive the inner cylinder 11 and these cylinders will rotate reversely to each other through the gear connections therebetween.

Bridging the outer cylinder 10 is a yoke frame 18 in which are removably carried stud journals 19, these having the hubs 15 journaled thereon. Centrally of the frame 18 is a handle 20, being fixed thereto in any suitable manner.

The gear 13 in one end of the outer cylinder 10 has formed therewith an annular cam 21 coacting with an annular companion cam edge 22 at the end of the inner cylinder 11 next thereto so that on relative rotary movements of the cylinders 10 and 11 these will be reciprocated with respect to each other. In other words, under the operation of the cams 21 and 22, companion to each other the inner cylinder 11 will be reciprocated within the outer cylinder 10. The bearing ends 23 of the frame 18 for the stud journals 19 are outstruck to afford a clearance for the reciprocating movement of the inner cylinder 11, these stud journals 19 being slidably fitted in said bearing ends 23 in addition to the rotatable fitting thereof. The gear 13 at the other end of the outer cylinder is formed with a retaining annulus 24 for the inner cylinder 11 and this annulus additionally constitutes a track for leaf springs 25 suitably fitted with the cylinder 11, the purpose of the springs 25 being for holding the companion cams 21 and 22 in contact with each other under reciprocation of the said inner cylinder 11 and the relative reverse rotation of the outer and inner cylinders with respect to each other.

The idling gears 17 are separably journaled on the yoke frame 18 and are in meshing engagement with the gears 13 and the pinions 16.

Under rotation of the outer cylinder 10 by contact with a surface the said outer cylinder effects a driver for the inner cylinder 11 and through the gearing connections between these cylinders one will rotate reversely to the other in the use of the razor.

The hair entering the slots in the cylinders 10 and 11 will be sheared or cut and there is no liability of the cutting of the skin during the use of the razor for shaving or hair removal.

The journals 19 are separably fastened in the hubs 15 of the inner cylinder 11 in any suitable manner.

During relative rotation of the cylinders 10 and 11 a reciprocating action of the inner cylinder 11 is set up within the said outer cylinder 10 when the razor is in use so that in this manner cutting action takes place in paths at right angles to each other.

20 The gears 13 in opposite ends of the outer cylinder 11 are held fast in place when within said cylinder in any suitable manner, it being necessary to remove one of the gears 13 when it is desired to extract the inner cylinder from the outer cylinder and, of course, the frame 18 is separated to allow for the separation of the said cylinders.

The spokes 14 support the inner cylinder 11 in conjunction with the hubs 15.

20 What is claimed is:

1. A razor of the character described comprising slotted interfitting relatively rotatable cylinders, gearing connections between the cylinders for reversely rotating the same with respect to each other, and means active between the cylinders for imparting reciprocation of one cylinder relative to the other.

2. A razor of the character described comprising slotted interfitting relatively rotatable cylinders, gearing connections between the cylinders for reversely rotating the same with respect to each other, means active between the cylinders for imparting reciprocation of one cylinder relative to the other, and a frame rotatably supporting the innermost cylinder.

3. A razor of the character described comprising slotted interfitting relatively rotatable cylinders, gearing connections between the cylinders for reversely rotating the same with respect to each other, means active between the cylinders for imparting reciprocation of one cylinder relative to the other, a frame rotatably supporting the innermost cylinder, and stud journals removably fitting the frame and rotatably connecting the innermost cylinder thereto.

4. A razor of the character described comprising slotted interfitting relatively rotatable cylinders, gearing connections between the cylinders for reversely rotating the same with respect to each other, means active between the cylinders for imparting reciprocation of one cylinder relative to the other, a frame rotatably supporting the innermost cylinder, stud journals removably fitting the frame and rotatably connecting the

innermost cylinder thereto, and a grip medially of the said frame.

5. A razor of the character described comprising slotted interfitting relatively rotatably cylinders, gearing connections between the cylinders for reversely rotating the same with respect to each other, means active between the cylinders for imparting reciprocation of one cylinder relative to the other, a frame rotatably supporting the innermost cylinder, stud journals removably fitting the frame and rotatably connecting the innermost cylinder thereto, a grip medially of the said frame, and means active between the cylinders for maintaining reciprocal relation thereof with respect to each other.

6. A razor comprising outer and inner cylinders, the latter being rotatably fitted within the outer cylinder, said cylinders having slots registering with each other, internal gears in the outer cylinder, pinions axially connected with the inner cylinder, idling gears between the said internal gears and the pinions and meshing therewith, a frame, and journals carried by the frame and rotatably supporting the inner cylinder.

7. A razor comprising outer and inner cylinders, the latter being rotatably fitted within the outer cylinder, said cylinders having slots registering with each other, internal gears in the outer cylinder, pinions axially connected with the inner cylinder, idling gears between the said internal gears and the pinions and meshing therewith, a frame, journals carried by the frame and rotatably supporting the inner cylinder, and companion cams on the outer and inner cylinders for imparting reciprocation to the inner cylinder on the rotation of both cylinders.

8. A razor comprising outer and inner cylinders, the latter being rotatably fitted within the outer cylinder, said cylinders having slots registering with each other, internal gears in the outer cylinder, pinions axially connected with the inner cylinder, idling gears between the said internal gears and the pinions and meshing therewith, a frame, journals carried by the frame and rotatably supporting the inner cylinder, companion cams on the outer and inner cylinders for imparting reciprocation to the inner cylinder on the rotation of both cylinders, and a grip carried by said frame.

9. A razor comprising outer and inner cylinders, the latter being rotatably fitted within the outer cylinder, said cylinders having slots registering with each other, internal gears in the outer cylinder, pinions axially connected with the inner cylinder, idling gears between the said internal gears and the pinions and meshing therewith, a frame, journals carried by the frame and rotatably supporting the inner cylinder, companion cams on the outer and inner cylinders for imparting reciprocation to the inner cylinder on the rotation of both cylinders, a grip carried by said frame, and springs active upon the said cylinders for holding the companion cams in working relation to each other.

GUSTAV BURGESON.
